[57] ABSTRACT

A method for making a releasably attachable tiepin is provided along with a method of tying a tie therewith. A tie is wrapped around a collar and its ends crossed, and one end of the tie looped over the front and up through the cross-loop and held in place adjacent to the loop by passing a pin through edges of the tie to lock it in place without a complete knot. The tie holding pin includes an elongated pin having an ornament on one end and a removably attachable ornament for attaching to the other end of the pin. The removable ornament is formed with a plastic insert therein having an aperture therethrough for frictionally engaging the pointed end of the pin. A metal point guide is placed over the plastic insert and has curved surfaces to direct the point into the aperture of the plastic insert. The edges of the ornament are rolled over to hold the plastic insert and plastic insert guide in the ornament.

6 Claims, 8 Drawing Figures

*Fig. 1.**Fig. 2.**Fig. 3.**Fig. 4.**Fig. 5.**Fig. 6.**Fig. 7.**Fig. 8.*## METHOD OF MAKING TIEPIN LATCHING MEMBER

BACKGROUND OF THE INVENTION

The present invention relates to a new method of tying a tie to provide a more attractive knot and a method of making an elongated tiepin for holding a tie in a preformed position.

In the past, a great many ties have been provided which are quickly and easily attached, or which are provided with more attractive knots that would normally be tied by the average individual getting dressed in the morning. These ties include snap-on bowties and preknotted ties which are snapped around the collar, as well as a great variety of ways for attaching ties with 15 readymade decorative knots.

The present invention provides a new method of tying a tie using an elongated tiepin of special design and which allows an individual to buy off-the-shelf ties and rapidly form the tie into an attractive knot with a minimum of time and effort. The present invention also provides a method of making a special elongated tiepin for use in tying the present tie, which tiepin may be manufactured inexpensively but provides an attractive ornament on either side of the pin, thereby providing 25 only decorative ornaments to open view.

Typical prior art patents may be seen in U.S. Pat. No. 3,093,830 for a Reversible Combination Tie-Vest, and in Necktie U.S. Pat. No. 2,148,973 in which snaps are used to provide a decorative knot for a tie. U.S. Pat. No. 2,843,850 illustrates a Necktie Form utilizing a snap to hold the tie in position, while U.S. Pat. No. 2,673,983 shows a Necktie Clasp for holding a necktie in proper position. U.S. Pat. No. 3,405,408 shows a tiepin using a Velcro material to hold a tie in proper position, while U.S. Pat. No. 1,769,755 illustrates a Necktie with special snaps for holding the tie in place.

SUMMARY OF THE INVENTION

The present invention relates to neckties and to a special tiepin for assisting in tying an attractive knot of any desired type. The method of tying a tie in accordance with the present invention includes wrapping a standard off-the-shelf tie around a collar, crossing one end of the tie over the other, and looping one end of the tie over the front and up through the loop formed by the crossing tie ends in a conventional manner. The top portion of the tie looped up through the crossing loop has its edges held towards each other while passing an elongated tiepin with a decorative head on one end through the edges to hold the tie in position adjacent the loop and then attaching a decorative end to the opposite end of the elongated tiepin to hold the tie in place to form a decorative tie knot.

The decorative tiepin has an elongated pin with an ornament on one end and a friction engaging ornament which is removably attached to the opposite end. The ornament for the opposite end may include an opening therein which has had a plastic insert inserted therewithin which plastic insert has an aperture running therethrough. A round, metal insert guide has an opening in the middle and is curved towards the middle opening, is placed over the plastic insert and the edges of the opening in the ornament is rolled over onto the insert guide. When a pin point is pushed against the insert guide it is directed into the aperture of the plastic insert, where it is frictionally engaged by the plastic as it

is pushed into the insert. The removable ornament may also be made by beginning with a predetermined sleeve member having one end partially closed but with an attachment opening through the partially closed end. The sleeve is removable, held by a holding member attached to the partially closed end opening, then forming a glass or other settable, fluid, decorative material onto the sleeve. The plastic insert with aperture therein may then be inserted into the sleeve and the insert guide placed thereover and the edges of the sleeve rolled onto the insert guide. The plastic insert may also be inserted in a second sleeve which is threaded in the sleeve with the ornament placed thereon.

BRIEF DESCRIPTION OF THE DRAWINGS

Other objects, features and advantages of this invention will be apparent from a study of the written description of the drawings, in which:

FIG. 1 illustrates an exploded perspective view of a 20 tiepin used in the present methods;

FIG. 2 is a front plan view of a tie in the process of being tied in accordance with the present method;

FIG. 3 is a rear plan view of a completed knot in accordance with the present method;

FIG. 4 is an exploded view of a tiepin ornament;

FIG. 5 is a front sectional view of an assembled tiepin ornament;

FIG. 6 is an exploded view of a second embodiment of a tiepin ornament;

30 FIG. 7 is an exploded view of a tiepin ornament sleeve and holding arm; and

FIG. 8 is an exploded view of yet another embodiment of holding the plastic insert in an ornament sleeve.

DESCRIPTION OF THE PREFERRED METHODS

Referring now to the drawings, FIGS. 1, 2 and 3, a preferred method of tying a tie in accordance with the present invention is illustrated. FIG. 1 has a tiepin 10 having an elongated pointed member 11 with an ornament 12 fixedly attached to one end thereof and a removably attached ornament 13 adapted to be attached to the point end 14 of the elongated pin member 11. Generally, the ornaments 12 and 13 would be identical in appearance but the ornament 13 would have the means for removably holding itself to the pin 11 which, in the present case, would be a friction engaging member including a plastic insert inserted in the end 19 which would have an aperture passing therethrough.

45 Since the plastic insert would be subject to damage by the point 14 of the pin portion 11 by missing the small aperture in the insert, a metallic pin guide is inserted thereover and the edge 15 of the ornament 13 is rolled over to hold the plastic insert and insert guide into the ornament 13, as will be described in more detail in connection with FIGS. 4 through 7. FIG. 2 illustrates a tie 16 wrapped in a conventional manner such as by crossing the tie ends and looping one end over the front and up through the crossed loop and down the front. The tie is wrapped around the collar with the narrow portion 17 and the two ends crossed in a conventional fashion. The large end of the tie 18 is looped up over the front and up through the loop formed by the crossing of the ends. Tie portion 18 is seen looped over in

60 FIG. 2 at which point the edges of the looped portion are pressed together and the pin 10 inserted through the two sides or edges of the portion 18 with the head 65

12 on one side and the pointed end 14 extending through the edge for engagement by the ornament 13 to hold the knot as illustrated in FIG. 3. The pin 10 always maintains the tie 16 with a neat locking shape which can be rapidly and quickly tied from a conventional tie. The knot 21 is in a generally triangular shape formed by portion 18 being wrapped over the loop portions of 17 and the ornaments 12 and 13 of the tiepin 10 being exposed, which tiepins can be changed on a regular basis to provide variation in addition to the variation of utilizing different ties.

FIGS. 4 and 5 illustrate one method of manufacturing the ornament 13 of the tiepin 10 in which the pointed end 14 of the elongated pin portion 11 is illustrated at one end of FIG. 4 with the ornament 13 at the opposite end of the exploded view with a portion cut away to show an opening 22 which has a bottom 23 with a small hole 24 extending into the bottom 23. A cylindrical plastic insert 25 has an aperture 26 passing therethrough which has been sized to fit a predetermined pin 11 and an insert guide 27 has an opening 28 passing therethrough and is curved so as to allow the point 14 of the pin 11 to slide along the curved surface into the opening 28 and thereby guide it into the opening 26 of the plastic insert 25 of the assembled ornament 13. The assembly of the ornament portion 13 provides for inserting the plastic insert 25 into the opening 22 of the ornament 13 and inserting the ornament guide 27 into the same opening over the plastic insert 25. The edges 15 of the opening 23 of the ornament 13 are then rolled 30 in a conventional roll technique over the edges of the insert guide 27 as illustrated in FIG. 5 to hold the insert 25 and guide 27 into the ornament 13 as illustrated in FIG. 5. Thus, the method involves producing an ornament 13 with an opening 22 therein, inserting the plastic insert with an opening therethrough, inserting an insert guide with an opening therethrough into the ornament member 13 and rolling the edge of the opening 22 of ornament 13 onto the insert.

FIGS. 6 and 7 illustrate a slightly modified embodiment in which a glass or other settable fluid material 30 forms the ornament tip. A specially built sleeve 31 fits onto the glass ornament 30 which sleeve has an opening 12 passing therewith to the opposite end 33 being partially closed and having a threaded opening passing therethrough. The plastic insert 34 with an opening 35 is similar to plastic insert 25, as is an insert guide member 36 with opening 37 similar to insert guide 27. The pointed member 14 of the pin 11 is the same in all of the embodiments. The method of making the ornament portion involves utilizing an arm 38 with a threaded end 40 which is inserted into the specially made metallic sleeve 31 and threaded into the sleeve holes 41 of the partially closed end 33. The holding member 31 then has the glass ornament 30 molded or formed directly thereupon at which point the inserting handle 38 is unthreaded from the sleeve 31 and the plastic insert 4 is inserted into the sleeve 31 open end and plastic insert guide 36 is inserted thereover into the sleeve 31 and the edges 42 of the opening 32 of the sleeve 31 is rolled over in a conventional manner and in the same manner as the method of FIGS. 4 and 5, to seal the plastic insert 34 with the insert guide 36 thereover. This method advantageously leaves the opening 41 so that the tip 14 can pass therewith if pushed too far into the opening 35 of the plastic insert 34 and will stop the pin 11 without damaging the point 14. Similarly, the drilled

out portion 24 in the bottom 23 of ornament 13 of FIG. 4 will accomplish the same result by letting the tip 14 of the pin 11 ease into the narrow opening before engaging the angled surfaces of the point 14 to prevent damage to the point.

In FIG. 8, the method in accordance with FIGS. 6 and 7 is modified to the extent that a second insert 50 has an open end 51 for the plastic insert 34 with opening 35 therethrough to be inserted. The sleeve 50 has a parabolic end portion 52 with an opening 53 and threaded portion 54. Once the plastic insert 34 is inserted in sleeve 50, sleeve 50 is threaded into sleeve 31 opening 32 having ornament 30 formed therein.

It should be clear at this point that a new method of tying a tie along with method for manufacturing a tiepin has been provided with several variations illustrated. However, this invention is not to be construed as limited to the particular forms disclosed herein since these are to be regarded as illustrative rather than restrictive.

I claim:

1. The method of making a decorative latching member comprising the steps of:
  - a. making a decorative member having an opening in one end thereof;
  - b. placing a plastic insert having an aperture therein into the opening of said decorative member;
  - c. placing an insert guide having angled surfaces and a center opening therethrough into said opening in said decorative member over said plastic insert; and
  - d. rolling the edges of said opening in said decorative member onto said insert guide to hold said insert guide and plastic insert in said decorative member whereby a pin of predetermined size may be guided into said aperture in said plastic insert by said insert guide and frictionally held by said plastic insert.

2. The method in accordance with claim 1 in which said decorative member having an opening in one end thereof includes forming a smaller opening in the bottom of said opening in one end of said decorative member for engaging the end of a pin inserted through said plastic insert without damaging the point of said pin.

3. A method of making a decorative jewelry latching member comprising the steps of:

- a. making a sleeve having one end partially closed with means for removably attaching a holding arm;
- b. removably attaching a holding arm through said sleeve to said partially closed end;
- c. molding a settable decorative material onto said sleeve;
- d. removing said removable attached holding arm from said sleeve;
- e. inserting a plastic insert having an opening therein into said sleeve; and
- f. sealing said plastic insert having an opening therein into said sleeve whereby inserting a pin of predetermined size into said opening in said plastic insert will frictionally engage and removably hold said pin thereto.

4. The method in accordance with claim 3 including the step of inserting a metal guide having an opening therethrough into said sleeve following the inserting of said plastic insert therein and sealing the said insert guide therein for guiding the point of said pin into the aperture of said plastic insert.

5. The method in accordance with claim 4 in which the step of sealing said plastic insert guide includes rolling the edges of the open end of said sleeve over onto said guide thereby sealing said plastic insert guide and said plastic insert into said sleeve.

6. The method in accordance with claim 3 in which

the step of inserting a plastic insert includes inserting said plastic insert into a second sleeve and threading said second sleeve into the first sleeve having decorative material molded thereon to thereby seal said plastic insert in said first and second sleeves.
